UNITED STATES PATENT OFFICE

2,459,727

BULK ICE-CREAM CONTAINER

Hubert B. Tillery, Kansas City, Mo.

Application March 7, 1946, Serial No. 652,624

2 Claims. (Cl. 229—6)

1

My invention relates to the art of paper manufacturers and particularly to boxes made from cardboard, or stiff paper and which can be made up from cut or stamped blanks.

The invention has for its objects to provide a box which can be shipped flat if desired, and readily assembled by the user; to provide a box with a removable or piston-like bottom that can be pressed out through the top of the box to eject or express the contents of the box.

Other objects will in part be obvious and in part will be pointed out hereinafter.

To the attainment of the aforesaid objects and ends invention also resides in those novel details of construction, combinations, and arrangements of parts, all of which will be first fully described and then be particularly pointed out in the appended claims, reference being had to the accompanying drawing in which:

Fig. 1 is a side elevation of a box according to my invention.

Fig. 2 is a central vertical cross-section of the same taken on the line 2—2 of Fig. 3.

Fig. 3 is a top plan view of the box, the lid being shown in dotted lines.

Fig. 4 is an inverted or bottom plan view of the box.

Fig. 5 is a view of the blank from which the sides and the bottom support of the box are made.

Fig. 6 is a plan view of a box bottom before bending over the flaps.

In the drawing in which like numerals of reference indicate like parts in all the figures, it will be seen that the box is an octagon-shaped box having the side faces 1 to 8 inclusive and a bottom 16. The side faces of the box are preferably of two different areas having different widths but all of one height. The faces 1, 3, 5, and 7 are the narrow ones while the faces 2, 4, 6 and 8 are the wider ones.

Fig. 5 is a plan view of the rectangular strip constituting the sides 1 to 8 inclusive and flap 9, of the box and the bottom retainers 10, and 13, 13^a. The strip is divided by parallel lines 11, 11^a, along which the strip is bent in the same direction. The strip is also bent or folded on the line 10 which extends from end to end parallel to the top and bottom edges of the strip. Diagonal folds 12 are also made to form triangular member 14, the bases of which lie in the fold line 10, the angles of folds 12 to fold 10 being 30°.

The bottom 16 of the box is made with sides 17 corresponding in number and width to that of the faces 1 to 8 inclusive and from the sides 17 rectangular flaps 18 project. The flaps 18 are

2

of a length somewhat less than the depth of the rectangular parts 13.

In making up the box, the flap 9 is glued or otherwise suitably secured to the inner surface of face 1. The bottom 16 with its flaps folded over at right angles may then be inserted in the box sides with the bottom edges of flaps 18 flush with fold line 10, after which the portions 13 are folded inwardly over the flaps 18 as shown in Figs. 2 and 3. In doing this the folds along the lines 11^a are automatically reversed and bends are made along the lines 12. The bottom 16 then rests in the groove the bottom of which is along the fold at 10. The triangular surfaces 14 then lie flat and form "locks," as it were, to prevent the rectangular parts 13 from coming unfolded.

The top or cover 20 of the box is formed of a blank shaped like that of the bottom 16. Both the bottom blank and the top blank have V-shaped cut-outs 19 so that when the flaps are folded the adjacent edges of the flaps will lie in close contact. By placing a band 21 tightly about the folded over flaps of the top 20 (see Figs. 1, 2 and dotted lines Fig. 3) the cover is completed. It is not necessary to fasten the strap or band 21 to the flaps of the top, although they may be secured together if desired, by gluing or in any other suitable way if desired.

When it is desired to dispense the contents of the box (ice-cream for instance) the lid is removed; after which the box may be inverted and the bottom pressed down (i. e. away from the parts 13, 14). The ice cream then will come out in the shape of the box.

While my improved box is particularly adapted for holding bulk ice-cream its use is not limited thereto and while it is preferably made of cardboard or any paper stock, other materials may be used for making the box, if desired.

From the foregoing description taken in connection with the accompanying drawing it is thought that the construction, method of assembly, and utility of the invention will be clear to those skilled in the art.

45 What I claim is:

1. In a box of the character described, comprising sides composed of a rectangular strip bent transversely along parallel lines to provide eight faces forming an octagon, said strip also being bent back inwardly along a longitudinal line to provide eight integral faces, alternate ones of which are bent along diagonal lines to provide four isosceles triangular surfaces having their bases along said longitudinal line, constituting "locks," the other four faces being rectangular

and being held in bent over positions by said "locks," and a bottom having an octagon form to fit into the octagon when assembled and having downwardly bent-over flaps to rest in the groove formed by said bent over rectangular faces and said "locks."

2. A two-piece folded blank box-body of octagonal form, comprising a side wall and a bottom, said bottom being composed of a flat octagonal body having downturned flaps, said side wall being composed of a strip having transverse fold lines defining eight faces and having a longitudinal fold line spaced from and parallel with and adjacent the lower edge of the strip defining integral bottom portions, the bottom portions of alternate faces having fold lines defining isosceles triangles having their bases along said longitudinal fold line, the said bottom portions being

10
5 folded in their operative position over the adjacent flaps of the bottom of the box, whereby the portions having the triangular members form "locks" to restrain said inwardly folded bottom portions against unfolding.

HUBERT B. TILLERY.
